UNITED STATES PATENT OFFICE

JOHN KAZOWSKI, OF CHICAGO, ILLINOIS, ASSIGNOR TO JOSEPH SILVERMAN, OF CHICAGO, ILLINOIS

KNEELING BENCH

Application filed April 9, 1930. Serial No. 442,751.

The present invention relates to church furniture generally and particularly to kneeling benches adapted to be used during religious worship and upon which the worshipper may kneel during participation in the religious ceremony.

It is usual in church furniture of this type to provide a cushion-like support upon which the worshipper may kneel and also to provide a support upon which the worshipper may place his arms or elbows. My invention is particularly concerned with providing a collapsible or folding type of kneeling bench which may be utilized to augment the capacity of the church during times when great crowds attend the services as well as to provide an article of this type where it may be desired to set up temporarily, as for example out doors, a place for worship.

Another object of my invention is to provide in church furniture of the above described type a kneeling bench which can be folded into collapsed position so as to occupy relatively small space when being stored or transported from place to place. Another object of my invention is to provide a folding kneeling bench which can be easily and quickly extended to supporting position and provided with means for securely holding the bench in that position. A further object of my invention is to provide a folding bench where the arm rest and the knee rest move together and can be extended in one operation. Still further, another object of my invention is to provide a convenient and easily accessible releasing means for releasing the holding means so that the bench can be easily and quickly folded from extended supporting position to its collapsed position.

Other objects and advantages of my invention will be apparent to those skilled in the art after a consideration of the following detailed description, taken in conjunction with the accompanying drawings, in which:

Figure 1 is a front elevation view of my improved kneeling bench;

Figure 2 is a sectional view taken substantially on the line 2—2 of Figure 1 and showing my improved kneeling bench in extended position;

Figure 3 is a front elevation view, corresponding to the view shown in Figure 1, and illustrating the position of my improved kneeling bench when in collapsed or folded position; and

Figure 4 is an enlarged view taken substantially on the line 4—4 of Figure 3.

The reference numeral 1 indicates in its entirety the main frame of my kneeling bench and which is seen to comprise the upright portions 2 and the intermediate horizontal portions 3 which, taken together, form a frame of inverted substantially U-shaped character. The legs or upright portions 2 are connected together by reinforcing transverse members 5, 6 and 7. These reinforcing members have flattened ends which are secured, as by welding or the like, to the respective legs 2. In this way an inexpensive but very durable frame is provided.

The arm rest is indicated by the reference numeral 10 and is seen to comprise a substantially rectangular frame 12 one longitudinal edge of which is pivoted to the intermediate horizontal portion of the frame 1 by means of hinges 14 riveted or welded to the frame 12 and to the intermediate portion 3 of the frame 1. The frame 12 carries a padded or cushioned support 16 which may be covered with leather or fabric if desired. A rigid backing member 17 serves to support the member 16 on the frame 12.

The knee rest is indicated in its entirety by the reference numeral 20. The knee rest 20 comprises a substantially rectangular frame 21 of such dimensions that the pad or cushion member 23 is spaced farther from the frame 1 than the arm rest 10 when the rests are in their extended position, as will be understood

from Figure 2. The frame 21 is pivoted to the lower portion of the uprights 2 by means of studs or pins 25. The pad or cushion member 23 is preferably secured to the frame member 21 by means of clips 26, see Figure 3.

Pivoted to the frame 21 is a supporting member 30 having rounded floor or ground contacting portions 32 as shown in Figure 3. The supporting member 30 is adapted to cooperate with the feet 35, formed of rubber or other suitable material, on the lower ends of the uprights 2 to support the kneeling bench in its upright and extended position, as will be clear from Figure 2.

15 The reinforcing transverse member 6 carries adjacent the uprights 2 an abutment 40 at each end thereof, and connecting the frame 12 of the arm rest to arms 42 secured, as by welding, to the frame 21 of the knee rest is 20 a pair of links 45, arranged as shown in Figure 2. A notch is formed in each of the links 45 so as to engage or embrace the abutments 40 to thereby hold the arm rest and the knee rest in extended position. For this purpose 25 the links 45 are resilient so as to allow them to move in contact with the abutments 40 until the notch 48 comes into juxtaposition therewith, whereupon the links 45 will spring laterally sufficient to immediately cause the 30 notches 48 to embrace the abutments 40 thereby locking the arm rest and the knee rest in extended upright position.

For the purpose of moving the links 45 out of locked engagement with the abutments 35 40 I provide a manually operated releasing member 50, see Figure 4, journaled in the upper tubular edge of the transverse reinforcing member 6 and which is provided at either end with an arm 52 adapted to engage 40 the links 45 and when rocked to move the links 45 out of their latched engagement with the abutments 40.

The releasing member 50 is easily and conveniently actuated by means of a handle 55 secured as by welding to the intermediate portion of the member 50, the transverse member 6 being provided with a cutaway section 57 to provide clearance for the handle 55 as well as for the spring 58 one end of 50 which is secured to the member 50 while the other end is secured to the member 6. The spring 58 is tensioned so as to withdraw the arms 52 from engagement with the links 45 to the position shown in Figure 2.

55 The supporting member 30, which is pivoted to the knee rest frame 21, is connected by a link 60 to each of the uprights 2, and as will be seen from Figure 2 the links 60 extend substantially parallel with respect to the sides 60 of the frame 21. The links 60 are each pivoted at their ends to the supporting member 30 and the uprights 2 so that as the knee rest 20 is swung upwardly the supporting member 30 will be folded down alongside the sides 65 of the frame 21, as shown in Figure 3. Each

of the links 60 is provided with a U-shaped reentrant bend 62 for the purpose of clearing the sides of the frame 21 whereby the links 60 occupy, when the kneeling bench is folded, a position between the sides of the frame 21 70 and the uprights 2.

The operation of my collapsible kneeling bench is believed to be obvious. When the bench is collapsed or folded and it is desired to set up the bench for use all that is necessary is to grasp the top portion 3 of the main frame 1 with one hand and with the other hand to grasp the uppermost portion of the knee rest frame 21, swinging the latter down to the position substantially that shown 80 in Figure 2. As the frame 21 is swung downwardly an upward thrust is exerted by the arms 42 and through the links 45 to the arm rest 10 to swing the same upwardly to the position shown in Figure 2. At the same time 85 the downward movement of the frame 21 causes the supporting member 30 to be swung from position alongside the frame 21 to the position shown in Figure 2, this being accomplished by virtue of the arrangement of the 90 links 60. While I have shown the links 60 as extending substantially parallel with respect to the sides of the frame 21, it is to be understood that such parallel arrangement is in 95 nowise necessary, the angular relation between the links 60 and the frame 21 depending upon the angular movement necessary to move the supporting member 30 from supporting position to a position alongside the frame 21 when latter is itself folded alongside the main frame 1.

When the parts have reached the position substantially that shown in Figure 2, the notch 48 in each of the links 45 comes to a point opposite the abutments 40 whereupon 105 the resiliency of the links 45 causes each of the notches 48 to snap into latched engagement with the abutments 40. In this way the arm rest, knee rest, and supporting member 30 are all maintained in extended position, so 110 that there is no likelihood of my kneeling bench suddenly and unexpectedly collapsing under the weight of the user.

When it is desired to return the bench to collapsed or folded position, all that is necessary to do is to grasp the handle 55 and to swing the same in a clockwise direction as viewed in Figure 2 so as to cause the arms 52 to engage the links 45 whereupon further rocking movement of the handle 55 and the 120 releasing member 50 will move the links 45 against their natural resiliency and thereby release the notches 48 from engagement with the abutments 40. While the notches 48 are held from engagement with the abutments 40 the knee rest frame 21 is grasped and swung upwardly, and as soon as the notches 48 are moved downwardly past the abutments 40 the handle 55 can be released, the spring 58 returning the same to its inactive 130

position shown in Figure 2. As the knee rest frame 21 is swung upwardly the arms 42 exert a downward pull on the links 45 which, in turn, swings the arm rest 10 downwardly and into folded position alongside the main frame 1 and between the uprights 2 so as to thereby occupy the minimum amount of space. The knee rest frame 21 also swings upwardly to a position alongside the main frame 1 and between the uprights 2, and it will be noted that the transverse reinforcing members 5 and 6 serve as limiting means for the collapsing movement of the arm rest and knee rest, respectively.

15 While I have described in connection with the accompanying drawings one preferred embodiment of my invention, it is to be understood that my invention is not to be limited to the specific embodiment shown but that, in fact, widely different means may be utilized in the practice of the broader aspects of my invention.

What I claim, therefore, and desire to secure by Letters Patent is:

25 1. A kneeling bench comprising a frame, an arm rest hinged to the frame and adapted to extend substantially horizontal and to fold downwardly so as to lie substantially within the confines of said frame, a knee rest hinged to the frame and adapted to extend substantially horizontal and to fold upwardly so as to lie substantially within the confines of said frame, means including a link extending intermediate its ends through said frame and pivotally secured to each of said rests and connecting said rests together so that as one swings downwardly the other swings upwardly, means to automatically lock the rests when they are moved into extended position, 35 and means on one of said rests for supporting said bench in upright position.

2. A collapsible kneeling bench comprising a frame having foot portions, an arm rest, a knee rest pivoted to said frame, means connecting the knee rest to the frame to hold the same in extended position, said connecting means being operable at will to permit said rest to be swung to collapsed position, means on the knee rest adapted to cooperate with said foot portions to support the bench in upright position, said means being adapted to fold against the knee rest, and means connecting the arm rest to the frame to hold the same in extended position, said 55 two connecting means including a pair of links extending from one rest to the other.

3. A collapsible kneeling bench of the class described comprising a frame of substantially inverted U-shape, supporting feet on the ends thereof, an arm rest pivoted to the intermediate portion thereof and adapted to be swung from extended position to folded position alongside the frame, a knee rest including a substantially rectangular frame pivoted to the first named frame and a support pivoted to the second named frame and a

port pivoted to the second named frame and cooperating with the feet on the first named frame to maintain the bench in upright position when the rests are extended, said knee rest also adapted to be folded alongside the first named frame, link means connecting the pivoted support to the first named frame so that when the knee rest is folded alongside the first named frame the support will be folded alongside the knee rest frame, and link means connecting the two rests so that the arm rest, knee rest and support can be extended in one operation.

4. A collapsible kneeling bench of the class described comprising a frame of substantially inverted U-shape, supporting feet on the ends thereof, an arm rest pivoted to the intermediate portion thereof and adapted to be swung from extended position to folded position alongside the frame, a knee rest including a substantially rectangular frame pivoted to the first named frame and a support pivoted to the second named frame and cooperating with the feet on the first named frame to maintain the bench in upright position when the rests are extended, said knee rest also adapted to be folded alongside the first named frame, link means connecting the pivoted support to the first named frame so that when the knee rest is folded alongside the first named frame the support will be folded alongside the knee rest frame, and link means connecting the two rests so that the arm rest, knee rest and support can be extended in one operation, said second named link means being resilient and having a notch so formed as to engage a portion of the first named frame so as to hold the rests and support in extended position.

5. A collapsible kneeling bench of the class described comprising a frame of substantially inverted U-shape, supporting feet on the ends thereof, an arm rest pivoted to the intermediate portion thereof and adapted to be swung from extended position to folded position alongside the frame, a knee rest including a substantially rectangular frame pivoted to the first named frame and a support pivoted to the second named frame and cooperating with the feet of the first named frame to maintain the bench in upright position when the rests are extended, said knee rest also adapted to be folded alongside the first named frame, link means connecting the pivoted support to the first named frame so that when the knee rest is folded alongside the first named frame the support will be folded alongside the knee rest frame, link means connecting the two rests so that the arm rest, knee rest and support can be extended in one operation, said second named link means having a notch adapted to engage an abutment on the first named frame so as to hold the rests in extended position, and spring retracted means to free the link means from the

abutment when it is desired to collapse the bench.

6. A collapsible kneeling bench comprising a frame, an arm rest pivoted to said frame, a knee rest pivoted to said frame, means for swinging said rests simultaneously into substantial horizontal position one above the other on the same side of said frame member, a support for said frame pivoted to said knee rest, and means connecting said support to said frame for swinging said support about its pivot.

In witness whereof, I hereunto subscribe my name this 5 day of April 1930.

JOHN KAZOWSKI.
